UNITED STATES PATENT OFFICE.

MATHIAS SCHONBACHLER, OF ROME, NEW YORK.

BRACKET.

SPECIFICATION forming part of Letters Patent No. 664,900, dated January 1, 1901.

Application filed April 5, 1900. Serial No. 11,593. (No model.)

To all whom it may concern:

Be it known that I, MATHIAS SCHONBACHLER, a citizen of the United States, residing at Rome, in the county of Oneida and State of New York, have invented certain new and useful Improvements in Brackets, of which the following is a specification.

This invention relates to new and useful improvements in adjustable brackets; and its primary object is to provide a device of simple and durable construction whereby suitable articles may be elevated to a desired height within a room. The device is especially adapted for supporting bread-dough, &c., near the ceiling of a room, thereby facilitating the raising thereof, as it is a well-known fact that the temperature at the top of a room is higher than at the bottom.

A further object is to provide a device that is neat and attractive, cheap to manufacture, and which may be readily fastened to a wall or other structure.

To these ends the invention consists in the novel construction and combination of parts hereinafter more fully described and claimed, and illustrated in the accompanying drawings, showing the preferred form of my invention, and in which—

Figure 1 is a side elevation of the device. Fig. 2 is a front elevation thereof. Fig. 3 is a top plan view. Fig. 4 is a cross-section on line $\alpha\alpha$, Fig. 2. Fig. 5 is a side elevation of a modified form of bracket, and Fig. 6 is a top plan view thereof.

Referring to said figures by numerals of reference, 1 is a standard having a longitudinally-extending groove 2 in the front surface thereof and a longitudinally-extending bead preferably arranged on the opposite surface thereof. A clasp 7 embraces the standard and is secured at the front thereof to the inner face of a plate 8, preferably rectangular in form. A brace 9 is secured at one end to the lower portion of the outer face of the plate, and its opposite end is secured to the center of an arc-shaped bracket 10, having arms 11, which embrace the plate 8 and are embedded at their ends in recesses formed within the sides of the plate.

Slidably mounted within the groove 2 is a 50 rod 12, the upper end of which is secured to the plate 8 in any suitable manner, preferably by means of a nut 13. The opposite end of the rod passes under the end of a strap 14, provided with a set-screw 15, and a handle 16 is secured to the end of the rod, as shown.

In operation a pan containing dough or other material is placed upon the bracket and slid upward by means of the rod 12 and its handle 16, said rod being held in adjusted position by means of the set-screw 15.

In Figs. 5 and 6 I have shown a modified form of bracket. In said figures the rod 12 passes forward through perforations formed within cross-strips 16, secured to the upper 65 surface of an arm 17, projecting from the face of the plate. The rod then bends downward and inward and is secured at its end to the outer face of the plate, near the bottom thereof.

In the foregoing description I have shown the preferred form of my invention; but I do not limit myself thereto, as I am aware that modifications may be made therein without departing from the spirit or sacrificing the 75 advantages thereof, and I therefore reserve the right to make such changes as fairly fall within the scope of my invention.

Having thus fully described my invention, what I claim as new, and desire to secure by 80 Letters Patent, is—

The combination with a standard of the character described, of a plate adjustably secured to the standard, an arm extending at right angles therefrom and having a series of 85 horizontal strips on the upper surface thereof, a rod slidably in the groove of the standard and projecting through the plate and strips, and secured to the lower portion of the outer surface of the plate.

In testimony whereof I affix my signature in presence of two witnesses.

MATHIAS SCHONBACHLER.
